Attorneys.

UNITED STATES PATENT OFFICE.

PHILIP COHEN, OF BUFFALO, NEW YORK.

HOSE SUPPORTER.

Application filed May 24, 1923. Serial No. 641,163.

To all whom it may concern:

Be it known that I, PHILIP COHEN, a citizen of the United States, residing at Buffalo, in the county of Erie and State of New York, have invented new and useful Improvements in Hose Supporters, of which the following is a specification.

This invention relates to improvements in hose supporters and particularly to men's garters.

Its objects are to provide a simple and inexpensive garter which will effectually and reliably support the hose without discomfort to the wearer and which is so constructed that liability to slippage of the same and the hose is prevented.

In the accompanying drawings:

Figure 1 is a side view of the garter in its applied position. Figure 2 is a front view thereof. Figure 3 is a face view of the garter removed from the leg. Figure 4 is a front view of a modified form of garter in its applied position.

Similar characters of reference indicate corresponding parts throughout the several views.

In the embodiment of the invention shown in Figs. 1-3, inclusive, the same consists of a main portion or band 10 of non-elastic material, such as leather, adapted to encircle the rear and adjoining sides of the constricted portion of the calf 11 in a forwardly inclined direction, and a substantially horizontal elastic portion or strip 12 extending laterally from one end of said main portion and arranged to engage the front or shin of the leg. At the junction of the main portion 10 with the elastic portion 12 is a tab 13 to the upright edges of which the opposing ends 40 of these portions are securely fastened, as by stitching, while a similar tab 14 is secured to the other end of said elastic portion. The garter is detachably connected to the leg of the wearer by means of suitable interlocking devices 15, 16 secured to the tab 14 and to the free end of the main garter portion, respectively. The latter may be provided with a friction slide-loop 17 for adjusting the length of the garter to suit the leg of the wearer.

Depending from the substantially upright portions of the tabs 13, 14 and preferably at an obtuse angle thereto, are integral supports or extensions 18, 19, respectively, to which the garment-clasps 20 are fastened. The length of the elastic strip is such that

the garment clasps lie substantially on opposite sides of the front portion of the leg and the same converge downwardly at an acute angle to said strip in the manner shown in Fig. 2. The clasp-support 18 of the tab 13 is, by preference, in line with and practically forms a continuation of the main garter band 10, as shown in Figs. 1 and 3. The clasp-support 19 of the other tab is inclined in the opposite direction and at substantially the same angle to the vertical as the companion clasp-support, so that when the garter is applied to the leg, said support 19 likewise forms a continuation of the garter band in the direction of its inclination relative to the leg, as shown in Fig. 2.

By this construction and arrangement, a garter is produced in which a straight upward and rearward pull on opposite sides of the front portion of the hose is effected, the pull radiating in a substantially straight line from the constricted portion of the calf to the fastening point of the garter with the hose. The elastic strip 12, aside from retaining the garter in its proper position on the leg of the wearer, maintains the clasp-supports 18, 19 in their correct relative positions, downward slippage of the garter and the hose on the leg being resisted by the combined gripping action afforded by said strip and the angular disposition of the band and its supports relative thereto.

If desired, the non-elastic band 10 of the garter may be provided with vent-holes or perforations 21, to prevent any accumulation of moisture due to perspiration.

In order to cause the band 10 to conform to the shape of the leg and to lie flatly against the same, it is slightly bowed or curved in the direction of its length, as shown in Fig. 3, to form a concave lower edge 22 and a convex upper edge 23.

In the modification shown in Fig. 4, the garter is provided with a single hose fastener 24 which is connected to the tab 25 secured to the free end of the elastic strip 12.

I claim as my invention:

1. A garter, comprising a pair of spaced tabs having downwardly-converging portions for receiving garment fasteners, the lower ends of said tabs being disconnected, an elastic member joined at its ends to the upper ends of said tabs, a leg-encircling band connected at one end to one of said tabs, and means for detachably connecting the other end of said band with the other

tab, the converging portions of said tabs being in line with the leg-encircling band in the applied position thereof and always maintained in the same relative converging position regardless of the degree of expansion or contraction of the elastic member.

2. A garter, comprising a pair of tabs each including a substantially upright portion and an obtusely-disposed depending portion for receiving a garment fastener, a transverse elastic-strip adapted to overlie the shin of the wearer and connected at its

ends to the upright portions of said tabs, the depending portions of the latter converging downwardly and spaced apart at their lower ends to lie on the opposite sides of the wearer's shin, and a leg-encircling band fastened at one end to the upright portion of one of the tabs and detachably connected to the corresponding portion of the other tab, the point of attachment of the fasteners with the garment being in line with the leg-encircling band in its applied position.

PHILIP COHEN.
